UNITED STATES PATENT OFFICE.

RUBEN STUEBNER, OF MILLVALE, PENNSYLVANIA.

RAIL-JOINT.

1,109,482.

Specification of Letters Patent.

Patented Sept. 1, 1914.

Application filed May 25, 1914. Serial No. 840,894.

To all whom it may concern:

Be it known that I, RUBEN STUEBNER, a citizen of the United States of America, residing at Millvale, in the county of Allegheny and State of Pennsylvania, have invented certain new and useful Improvements in Rail-Joints, of which the following is a specification, reference being had therein to the accompanying drawing.

10 This invention relates to rail joints, and has for its object to provide a device of such class, in a manner as hereinafter set forth, for connecting the opposing ends of a pair of track rails together without the 15 employment of nuts and bolts at the same time providing for the expansion and contraction of the track rails due to climatic conditions.

Further objects of the invention are to 20 provide a rail joint, which is simple in its construction and arrangement, strong, durable, conveniently set up, thoroughly efficient in its use, and inexpensive.

With the foregoing and other objects in 25 view, the invention consists of the novel construction, combination and arrangement of parts as hereinafter more specifically described and illustrated in the accompanying drawings, wherein is shown an embodiment 30 of the invention, but it is to be understood that changes, variations and modifications can be resorted to which come within the scope of the claims hereunto appended.

In the drawings wherein like reference 35 characters denote corresponding parts throughout the several views:—Figure 1 is a side elevation of a pair of track rails showing the adaptation thereto of a rail joint in accordance with this invention, Fig. 2 is 40 an enlarged side elevation showing a portion of the joint, Fig. 3 is a sectional plan, broken away of the joint, and Fig. 4 is a transverse sectional view, through one of the track rails and the joint.

45 Referring to the drawings in detail, 5 and 6 denote a pair of track rails, and each of which includes a head 7, web 8 and base 9. The web 8 of each of the track rails is provided with a series of longitudinally ex- 50 tending elongated openings 10.

Arranged at each side of the track rails 5 and 6, is a splice bar 11, and each of which has its lower end provided with a flange 12, which abuts against the base 9, as well as 55 projects laterally therefrom. Each of the splice bars 11 extends from the base 9 to

the head 7, and has its inner face, centrally thereof, longitudinally recessed as at 13. The upper and lower edges of each of the splice bars 11 are beveled as at 14, whereby wedging action will be set up between the splice bar and the head 7 and base 9 of the track rail when the splice bar is mounted in position due to the fact that the lower face of the head 7 and upper face of the base 9 are beveled. Each of the splice bars 11 is provided with a series of longitudinally extending elongated openings 15, which when the splice bars 11 are mounted in position, are arranged in alinement with the openings 10 70 in the web 8.

The outer face of each of the splice bars 11, is provided with an upper and a lower projecting portion 16 and 17 respectively, and each of said projecting portions intermediate its ends is provided with a concavity 18. The ends of the projecting portions are oppositely beveled with respect to each other and the said projecting portions are arranged parallel to the side walls 80 of the openings 15. The concavities 18 of certain of the projecting portions are arranged parallel to the inner ends of certain of the openings 15, while the concavities 18 of the other of the projecting portions 85 are arranged parallel to the inner ends of the other of said openings. As illustrated, each of the fish plates is provided with six openings 15 and the concavities 18 of certain of the projecting portions are arranged at the inner ends of three of the openings 15, and the concavities of the other of the projecting portions are arranged at the inner ends of the other three of the openings 15. 95

Extending through the alining openings 10 and 15, are retaining members, and each of which comprises a cylindrical body portion 19, having a rectangular head 20 at each end thereof. The termini of the body 100 portion 19 are disposed centrally with respect to the inner faces of the heads 20. The inner faces of the heads 20 at each side of the termini of the body portion 19 are oppositely beveled as at 21 and the 105 said beveled inner faces of the heads 20 of each retaining member seat in a pair of opposed concavities 18, under such conditions locking the fish plates and track rails 5 and 6 together.

110 The openings 10 and 15 are of a length to provide for the passage of a head 20

when mounting a retaining member in position and when mounting the retaining member in position, the heads 20 extend longitudinally. After the retaining member has been positioned with the heads thereof extending longitudinally, the retaining member is turned so that the heads 20 will extend vertically. The retaining member is then shifted and the beveled portions 21 of the heads 20 will ride against the beveled faces at one end of a pair of alining projecting portions 16 and 17, and the heads 20 will ride up the beveled surfaces of the projecting portions. The splice bars will be drawn toward the webs 8, and this action will continue until the beveled portions 21 of the heads 20 will seat in the concavities, under such conditions the splice bars and track rails being locked together. When a retaining member is in position, four locking engagements are had between the heads thereof and the splice bars and four locking engagements are provided by the two upper projecting portions, the two lower projecting portions, the concavities 18 in the four projecting portions, and the four beveled surfaces of the pair of heads 20 of the retaining members. Although each of the splice bars is illustrated as provided with six openings, it is obvious that this number can be increased or diminished, and although six retaining members are illustrated in connection with the joint, yet it is obvious that this number can be increased or diminished if desired.

What I claim is:

1. A rail joint comprising a pair of fish plates adapted to be positioned against the sides of a pair of track rails and formed

with openings, each of said splice bars on its outer face provided with pairs of projecting portions arranged parallel to the side walls of said openings, each of said offsets having its outer face provided with a centrally disposed concavity and each of its end portions beveled, the bevel of the ends of each projecting portion being opposite with respect to each other, retaining members extending through said openings and further adapted to extend through the webs of the track rails and having heads at the ends thereof, each of said heads having its inner face beveled in opposite directions, the beveled inner faces of each of the heads of a retaining member seated in opposite concavities for locking said splice bars and track rails together.

2. A rail joint comprising a pair of splice bars adapted to be positioned against the sides of a pair of track rails and each provided with a plurality of openings, each of said splice bars further having its outer face formed with projecting portions having concavities and beveled surfaces leading to the ends of the concavities, and retaining members extending through said opening and further adapted to extend through the webs of the rails and each provided with a pair of heads having the inner faces thereof oppositely beveled, the beveled inner faces of said heads engaging in said concavities for locking the splice bars and track rails together.

In testimony whereof I affix my signature in the presence of two witnesses.

RUBEN STUEBNER.
